CARBURETOR

Walter H. Weber, Detroit, Mich., assignor to
 Detroit Lubricator Company, Detroit, Mich., a
 corporation of Michigan

Application April 6, 1929, Serial No. 352,968

31 Claims. (Cl. 261—34)

My invention relates to new and useful improvements in carburetors, and more particularly to a carburetor of the plain tube type.

An object of my invention is to provide a carburetor which will supply a proper combustible fuel mixture for all conditions of operation of an internal combustion engine.

Another object is to provide means which will augment the proportion of liquid fuel to air for acceleration from low speeds corresponding to positions of part open throttle.

Another object is to provide means to increase the normal richness of the fuel mixture for low and high engine speeds and for maximum power demands, and to decrease the normal richness of the fuel mixture for intermediate engine speeds.

Another object is to provide means to prevent decrease in the richness of the fuel mixture during intermediate engine speeds for the "warming-up" of the engine.

The invention consists in the improved construction and combination of parts, to be more fully described hereinafter, whereby proper fuel mixture may be supplied to an internal combustion engine, and the novelty of which will be particularly pointed out and distinctly claimed.

In the accompanying drawings, to be taken as a part of this specification, I have fully and clearly illustrated a preferred embodiment of my invention, in which drawings—

Figure 1 is a view in side elevation of my improved carburetor;

Fig. 2 is a top plan view thereof, partially in horizontal section;

Fig. 3 is a view thereof in longitudinal vertical central section;

Fig. 4 is a view in partial vertical section on the line 4—4 of Fig. 2;

Fig. 5 is a top plan detail view of the bottom part of the carburetor, and

Fig. 6 is a detail view in vertical section on the line 6—6 of Fig. 2.

Referring to the drawings by characters of reference, 1 designates, generally, a carburetor casing, preferably comprising a bottom part or section 2 and a top part or section 3, which are joined together by studs 3', or the like, on a substantially horizontal plane, and which are preferably die-cast, though it is of course apparent that any other suitable method of forming the sections may be employed. In the section 2 are an air chamber 4 and a liquid fuel reservoir or constant level float chamber 5, which are separated by a wall 6 in which are a plural-

ity of substantially vertical wells or chambers 7, 8 and 9, of which the chamber 7 is open to the float chamber 5 and serves as a valve chamber therefor. Each of the chambers 4, 5, 7, 8 and 9 is open at its upper end. Secured to the under side of the section 2, in any suitable manner, beneath the float chamber 5, is a cup-like member 10 which cooperates with a downward open recess 11 in section 2, to form a strainer chamber having an inlet passage 12 terminating in a nipple 13 for connection to a source of liquid fuel supply and having a passage 14, see Fig. 4, in the bottom wall of section 2, and which terminates preferably centrally beneath the valve chamber 7. Clamped between the member 10 and section 2, is a filter medium 15, preferably a wire strainer of fine mesh which separates the passages 12 and 14. The chamber 7 connects with passage 14 by a substantially vertical passage 16, which at its top is of enlarged diameter and internally threaded, as at 17, to receive the lower end of a sleeve member 18 which is screw-threaded therein. Through the sleeve adjacent its lower end are ports 19 which open into chamber 7, and below these ports 19 the sleeve has an internal annular shoulder 20 serving as a valve seat. A needle valve 21 cooperates with seat 20 to close the inlet passage 16, and has a stem 22 guided for reciprocation in the sleeve 18. The valve 21 is adjustably supported, as by threaded engagement with a collar 23 which hangs in the arms of a yoke 24 at one end of a float lever 25 which is pivotally supported on a bearing pin 26 secured in the wall of the casing 1. Rigid with the other end of lever 25 is a float member 27, preferably a hollow sealed sheet-metal body.

Within the air chamber 4 is a vertical boss or web member 28 which rises from the bottom wall of the air chamber and extends from the wall 6 beyond the vertical center line of the air chamber. Through the web member 28 is a vertical bore 29, substantially coaxial with the center line of the air chamber and which is constricted at its upper end to provide a downward facing shoulder 30 below which the bore 29 is internally threaded, as at 31. The bottom end of bore 29 is sealed by a plug member 32. Between the bore 29 and the bottom of the float chamber 5 is a fuel feed conduit or passage 33. Projecting vertically upward from the boss 28 to a point slightly above the normal liquid level line L—L, is a fuel discharge nozzle or tube 34 which has a circumferential flange 35 adjacent its lower end which engages the shoulder 30. Abutting the under

side of flange 35 and surrounding the tube 34, is a ring or sleeve member 36 which seats on a plug member 37 threaded into the bore 29 and serving to force the flange 35 against the shoulder 30. 5 and to tightly clamp and seal member 36 between member 37 and the tube 34. Through plug member 37 is a port 38 concentric with bore 29, and which is calibrated to provide the main liquid fuel supply jet or inlet for the carburetor. 10 Through the ring member 36, is a port 39 which is calibrated to regulate the degree of sub-atmospheric pressure which acts on the main jet 38. From the bottom of the well or chamber 8 which is of reduced diameter to provide an upward facing shoulder 40, a passage or conduit 41 leads through the boss 28, to the bore 29 at the member 36 for communication with port 39. This port 39 also serves as a fuel inlet from the chambers 8, 9 to the mixing chamber and provides a 15 supply of fuel which is supplemental to the supply of fuel from the main fuel inlet or jet 38. Between the bottom of chamber 8 below shoulder 40 and the bottom of the chamber 9, is a passage or port 42. Within the chamber 8 is a tight 20 fitting plug member 43, which seats on the shoulder 40 and has a longitudinal bore 44 therethrough. At its upper end the member 43 has a circumferential end recess 45 which provides, with the wall of chamber 8, an annular reservoir 25 or chamber. The member 43 extends upward preferably slightly beyond the bottom section 2, and the recess 45 extends downward substantially to the line L—L of the normal liquid fuel level. In the section 2 and concentric with the 30 chamber 9 is a vertical bore 46 which is of reduced diameter, as at 47, at its inner or upper end, which opens into chamber 9 to provide a valve port for a purpose to be described. The bottom end of the bore 46 is closed and sealed 35 by a plug member 48 having an upward or inwardly open cylindrical longitudinal recess 49 of a diameter larger than port 47. Connecting the bore 46 below port 47 with the passage 33, is a passage or conduit 50 by which liquid fuel 40 may be supplied to the chambers 8 and 9 from the fuel reservoir 5. The passage 33 may be provided with a drain port 51 closed by a screw plug 52, and which serves as a means for emptying 45 the carburetor of liquid fuel. The air chamber 5 is supplied with air by an air inlet passage or conduit 53 having its longitudinal center line substantially horizontal. Extending across the air inlet 53 is a substantially horizontal shaft 54 which projects through the walls of the conduit 55 50 and is journaled therein. Fixed rigidly on the shaft 54 within the conduit is a disc member 55 comprising an air control or choke valve whereby the ratio of fuel to air may be controlled. Rigid with one end 56 of shaft 54, is a lever arm 60 55 57 having securing means 58 for the end of a valve operating rod or wire (not shown) by which an operator may regulate the position of valve 55. A support and guide member 59 for the rod or wire may be secured to the casing 1, if desired. 60 Rigid with the other end 60 of the shaft 54, is a cam member 61, for a purpose to be described, having a cam groove 62 in its periphery. The base of the groove 62 is arcuate at one end, as at 63, and merges into a straight portion 64 65 tangent thereto which terminates in a straight portion 65 at an angle to portion 64. On the outside of the casing 1 at the upper end of the chamber 9, is a boss 66 which extends outward substantially to the plane of the groove 62. 70 Journaled on a pin or screw 67 projecting from 75 boss 66, is a lever member 68, preferably a bell-crank, one end 69 of which extends into the groove 62 so that rotation of the cam member 61 will depress the end 69 of the lever. At its opposite end the lever 68 has an arm portion 70 which extends upward and then substantially horizontally inward over chamber 9. A spring means 71 having one end secured to the casing 1 and the other end secured to the lever 68 normally acts to maintain the lever end 69 in contact with the base of the cam groove 62. 10 The top section 3 overlies the chambers 4, 5, 7, 8 and 9 and has a cover portion 72 for the reservoir 5 and chambers 7 and 9, and a portion 73 extending upward therefrom which has a substantially vertical cylindrical bore 74 therethrough concentric with the nozzle 34 and forming the mixture outlet 74'. Through the cover portion 72 is an air inlet port 72' opening into the reservoir 5 above the normal fuel level to maintain atmospheric pressure on the fuel therein. A dirt shield 73' may be provided to prevent foreign matter from entering the port 72'. Within the bore 74 and extending downward into the top of the chamber 4 to a point below the top of nozzle 34, 25 is a choke tube or venturi 75, which forms the lower part of the carburetor mixing chamber 76, as is well known in the art. The Venturi tube 75 is preferably held in position by a set screw 77, or the like, threaded through the casing 1 30 and having a lock nut 78. At the bottom of the annular recess or reservoir 45 is a port 79 in the side wall of chamber 8, which aligns with a port 80 in the tube 75 and which is slightly above the most constricted portion of the venturi. Projecting substantially horizontally into the venturi or mixing chamber and seated and sealed in the port 80, is a discharge tube 81 having a calibrated discharge aperture 82. Extending diametrically 40 across the bore 74 above tube 75 and preferably substantially in the vertical plane of the longitudinal center line of the air inlet 53, is a shaft 83 which is journaled in the walls of portion 73, and the ends of which project therefrom. Fixed on the shaft 83 to turn therewith, is a disc member 84 within the bore 74 and which serves as a throttle member to control the sub-atmospheric pressure in the mixing chamber and the discharge of mixture therefrom. Rigid with that end of the shaft 83 which overlies the air inlet 53, is a lever member 85 having stop arms 86 which cooperate with a boss or abutment 87 projecting from the portion 73 to limit the rotation of the shaft 83 to substantially seventy-five degrees. The arm 86 which limits closing of the throttle valve is 50 preferably provided with an adjustment means 88, such as a screw threaded therethrough and held in adjusted position by means of a lock screw 88'. Journaled or pivoted on the opposite end of the shaft 83 is a lever arm 89 which extends to a 60 point substantially centrally over the chamber 9. Rigid with the shaft 83 and on the end thereof beyond arm 89, is an operating member 90 having a finger or lug 91 which extends beneath the arm 89 so that rotation of shaft 83 to move the throttle valve 84 toward closed position will raise the arm 89 while opening of the throttle valve will allow downward movement of the arm 89. Through the cover portion 72 is an aperture 92 registering with chamber 9. Around the aperture 92 the bottom 70 face of the portion 72 is recessed to provide a downward facing shoulder 93 for cooperation with a peripheral flange 94 on a hollow cap member 95. The body of the member 95 projects upward through the aperture 92 and the shoulder 93 75

clamps the flange 94 tightly against the section 2. Through the top wall of the member 95 is a slot 96 transverse to the axis of shaft 83. Within the chamber 8 is a piston 97 which is connected 5 to the free end of arm 89 by a rod or link 98 which passes freely through slot 96. The under or working face of the piston 97 is just above the plane of the normal liquid level when the throttle is in "idle" position (see Fig. 4). Positioned between 10 the piston 97 and the top wall of member 95, is an expansion member 99, preferably a coil spring under compression and which surrounds rod 98. Spring 99 normally urges the arm 89 into engagement with lug 91 and tends to move the piston 15 97 downward. In the rod or link 98 is a notch 100, which when the piston 97 is in its uppermost position, i. e., with the throttle valve substantially closed, will be above the cap member 95 and in cooperable relation to the horizontal lever arm 20 portion 70, so that when the air choke valve 55 has been moved more than one-quarter toward closed position, spring 71 will force arm 70 into the notch 100 to prevent downward movement of piston 97. Depending centrally from the piston 97 25 is a control means, preferably a cylindrical member 101 of a diameter substantially equal to the diameter of the valve port 47, so that the member 101 will have a tight sliding fit therein to effectively seal the port 47. The lower end of member 30 101 extends into port 47 when the piston is in its uppermost position, i. e., throttle in "idle" position, and has a bevel or conical taper, as at 102, to permit a predetermined flow through jet 47. The taper 102 preferably starts at about one 35 sixty-fourth to one thirty-second of an inch above the valve port 47 and the bottom of chamber 9. The member 101 is hollow, having a bore 103 which is closed at its ends. At the lower end of bore 103 and just above the taper 102, is an inlet 40 port 104 to the bore 103, and at the upper end of the bore 103 is an outlet port 105 into the chamber 9. The length of the port or jet 47 is such that the inlet port 104 will be cut off until the throttle valve has been opened a distance corresponding to a level road car speed of fifty miles 45 or more per hour. When the throttle valve passes beyond such a position, the member 101 will have been depressed sufficiently to carry the port 104 below the wall of port 47, so that fuel will flow 50 under the gravity head in the float chamber 5 to bore 46 through port 104, bore 103, and port 105 into chamber 9, providing a submerged fuel jet. In the side wall of the chamber 9 at its upper end, is a slot 106 open to the atmosphere, which 55 terminates at a point slightly below piston 97 to insure atmospheric pressure on the liquid in chamber 9 when the piston is in position corresponding to "idle", and to permit the well 9 to fill rapidly when the throttle is in idling position. 60 Over the middle chamber 8 is a boss 107 which rises from portion 72 and extends laterally from portion 73. In the boss 107 is a substantially cylindrical chamber 108, closed at its upper end, and which aligns with and forms the upper end 65 of chamber 8. Through the boss 107 above chamber 108 is a bore 110 which is transverse to the shaft 83. In the bore 110 is an annular shoulder 111 forming a valve port beyond which the bore 110 is threaded to receive the threaded stem of a 70 needle valve 112 which controls the area of the 75 port 114. A spring means 113, preferably a coil spring, surrounding the stem of valve 112 is held under compression between a head 114 on the stem and the boss 107, to hold the valve 112 in adjusted position. A boss 115, substantially in the horizontal plane of bore 110, extends externally for substantially ninety degrees around the portion 73. Through the boss 115 is a passage 5 or conduit 116 communicating at one end with the bore 110 beyond valve seat 111 and at its other end opening into the mixture outlet 74' (see Fig. 6). In the end of passage 116 which communicates with bore 74, is a plug member 117 having a calibrated discharge port 118 therethrough. Through the upper end wall of chamber 8 is a vertical aperture 119 which opens into the bore 110 beyond the valve seat 111. Seated in the aperture 119 and depending from the upper end wall of chamber 8 is a tube 120 which extends through the bore 44 of member 43 in spaced relation to the side wall of the bore to provide an annular air passage. The tube 120 terminates below the passage 41 substantially at the bottom of chamber 8 and has a calibrated inlet port 121 in this bottom end.

The operation of my carburetor is as follows: 25 When it is desired to start the engine (not shown), to which the carburetor is attached, the air inlet choke valve 55 is rotated to close the air inlet 53 by means of the usual dash control (not shown) connected to the lever 57 which is fixed 30 on the choke valve shaft 54 which will increase the ratio of fuel to air for engine starting. The cam member 61 which is fixed to the opposite end of the choke valve shaft rotates with the latter, and during the first approximately quarter rotation counterclockwise of Fig. 1, i. e., toward valve closing position, releases the end 69 of bell-crank lever 68, permitting the spring means 71 to 35 rotate lever 68 counterclockwise to cause the substantially horizontal end portion 70 to engage 40 in the slot or notch 100 in the pump piston link 98 to prevent the latter, and hence the piston 97, from moving downward as the throttle valve 84 is opened. The throttle valve is then opened slightly beyond idle position and the engine is 45 ready to be started in the usual manner. The high sub-atmosphere pressure created in the mixing chamber 76 with the air inlet 53 thereto closed, when the engine is turned over, draws the 50 desired quantity of liquid fuel from the main and idling nozzles 34, 118, respectively, together with a little air from the idling air bleed 111', to supply the desired "overrich" mixture for engine starting. As soon as the engine "fires", the air inlet choke valve 55 is opened partially, enough to supply sufficient air to dilute the "overrich" 55 starting mixture to keep the engine running, the quantity of air depending upon the atmospheric and engine temperatures and the requirements of the engine. The "richness" of the "warming-up" mixture depends upon the quantity of air supplied to the mixing chamber 76, which is regulated by the position of the air inlet choke valve 55, and the average operator is soon adept in locating the proper choke valve position. As 60 long as the choke valve 55 is maintained in any effective partly choked position (that is, more than approximately one-quarter closed), the lug or dog portion 70 on the bell-crank lever 68 remains engaged in the notch 100 of the pump piston link 98, thereby keeping the pump disengaged from actuation by the throttle valve 84. The pump piston 97 throughout the "starting" and "warming-up" operations of the carburetor remains in 65 its uppermost position, as shown in Fig. 4, and 70 75

thereby keeps the pump chamber fuel supply orifice or jet 47 open, and hence causes the jet 47 to feed an additional amount of fuel, which is constant in quantity per unit of time, to the main nozzle 34 via the bottom of chamber 9, port 42, bottom of chamber 8, passage 41 and orifice 39. During these "starting" and "warming-up" operations the pump chamber 9 being open to atmosphere, cooperates with the chamber 8, also open to atmosphere, to provide an atmospheric fuel well of the desired capacity, the chamber 9 compensating for the decreased volumetric capacity of chamber 8, due to the sleeve 43, so that the chambers 8 and 9 together comprise the atmospheric leg of a U-shaped passage or conduit having the nozzle discharge tube 34 as the other or fuel leg thereof, and which legs are in communication by reason of the passage 41 so that the passage leg 8, 9 and the passage leg 34 function as a U-tube. The additional feed or discharge of liquid fuel from the atmospheric well or leg of the U-shaped passage (chambers 8 and 9) is constant in quantity per unit of time, thereby enriching the main fuel mixture inversely as the speed of the engine. When the engine has become sufficiently warm, which will be apparent from its performance, the choke valve 55 is returned to its normally open position, as in Fig. 3, rotating cam 61 clockwise of Fig. 1 to depress end 69 of the bell-crank lever 68, thereby to disengage lever portion 70 from the notch 100 in the pump piston link, restoring the pump piston 97 to control by the throttle valve 84 and permitting it to function normally. In the event the operator opens his throttle valve 84 before he closes the choke valve 55 for "starting", the bell-crank lever lug portion 70 will bear laterally against the pump piston link 98, due to the spring means 71 acting on the bell-crank lever, and the lug or dog portion 70 will engage in the notch 100 of the link only when the throttle valve 84 is returned to "idle" position. It may be noted that the position of the pump piston 97 does not affect engine starting in any way, as is apparent, and since the throttle valve 84 is soon returned to "idle" position after the engine "fires", the sequence in which the operator closes choke valve 55 and opens the throttle valve 84 is of little importance.

As the throttle valve 84 is gradually opened from "idle" position to speed up the engine, the throttle shaft lug 91 will be moved downward, permitting the piston spring 99 to move the piston 97 downward and the tapered valve 102 carried thereby. As the piston valve 102 is moved downward, it will decrease the quantity of fuel admitted to the chambers 8 and 9, thereby causing a lowering of fuel level in the chambers, decreasing the working head and decreasing the richness of the supplementary mixture supplied through the idling jet 118 as the richness of the mixture supplied through the main jet 34 increases. At a throttle opening corresponding to a level road car speed of substantially fifteen miles per hour, the piston valve 102 will have cut off the fuel inlet port or jet 47 to the pump chamber 9, and the well, comprising chambers 8 and 9, will be emptied. During the period of throttle opening when the inlet 47 to the pump chamber 9 is cut off by member 101, atmospheric air entering the top of the chamber 8 via passage 109 from the reservoir 5, will pass down through bore 44 around the idling tube 120, through the calibrated jet 39 at the end of the horizontal passage 41 and into the bore of the main nozzle

34, so that an emulsion of air and fuel will be formed above jet 38 and issue from the main nozzle 34 to the mixing chamber 76. This emulsion, which increases in quantity of liquid fuel relative to air as the throttle valve is opened, will provide a proper and economical mixture for all car speeds and loads corresponding to all level road car speeds below fifty miles per hour. The fuel inlet port 47 to the pump chamber 9 will remain closed by the piston valve member 101 until the throttle valve 84 has been opened to a position corresponding to fifty miles per hour level road car speed. For all throttle valve positions corresponding to level road car speeds above fifty miles per hour, the inlet port 104 will have been moved downward so that it will be below the wall of the inlet port 47, and liquid fuel will flow through port 104, through the hollow bore 103, and from the outlet port 105 into the pump chamber 9, thus constituting a submerged fuel jet. The liquid fuel from this submerged jet will flow through port 42 into chamber 8 and be fed as an emulsion by the air entering the top of the chamber 8 from reservoir 5, through the calibrated jet 39 to the bore of the main nozzle 34. This additional supply of fuel from inlet 38 to the main nozzle and is dependent entirely upon the throttle position and enters the nozzle as an emulsion to increase the richness of the mixture fed to the engine at level road car speeds above fifty miles per hour and for all throttle openings required to develop maximum power regardless of car speed.

So much of the operation as has been described has not dealt with the problem of obtaining "punch" i. e., rapid acceleration. For level road car speeds of about fifteen miles per hour or more, the engine has sufficient momentum to accelerate rapidly upon a quick opening of the throttle without the necessity of enriching the fuel mixture; but for car speeds below fifteen miles per hour some means must be employed to obtain the necessary enriched mixture to give "punch". This problem has been solved by employing the pump piston 97 operating in the atmospheric leg of the U-shaped passage. With the car travelling at a speed below fifteen miles per hour so that chambers 8 and 9 are filled or partially filled, and with the lug 70 disengaged from notch 100, quick opening of the throttle valve 84 will permit spring 99 to expand, forcing piston 97 downward to expel the liquid fuel from chamber 9 through port 42. Since normal operation to obtain rapid acceleration would be to quickly open the throttle valve 84 to its maximum open position, the piston 97 will force all of the fuel in chamber 9 into chamber 8, and due to plug or sleeve 43, the major portion of this shot of solid liquid fuel which is not forced by the piston through port 39 into the main nozzle 34, will overflow the top of plug 43 and be caught in chamber 45. The chamber 45 is open to atmosphere by reason of passage 109, so that the quantity of liquid fuel caught in chamber 45 will flow under the difference of pressures and by gravity head through the nozzle 81 and calibrated port 82. Since the port 39 is relatively small, very little of the fuel discharged from chamber 9 will be forced therethrough, and the port 82 is calibrated so that this additional fuel for acceleration fed to chamber 45 and discharged therefrom into the mixing chamber 76, will be prorated over as long a period of time as possible, consistent with the desired enrichment of the fuel mixture.

It is to be noted that when inflow of fuel to chamber 9 is cut off by opening of throttle valve 84, fuel will not be trapped in the chamber 9, due to cut-off of the passage 106 by piston 97, because the piston 97 intentionally does not fit tightly enough in chamber 9 to occlude all air therefrom.

It is also to be noted that the air which normally bleeds into the mixing chamber through the calibrated pump discharge orifice 82, is so small in volume per unit of time that it does not affect the mixture supplied and is negligible.

It may also be noted, as the throttle valve is gradually opened beyond a position corresponding to fifty miles per hour, that the port 104 will be gradually uncovered so that the emulsion supplied to the port 39 will increase in richness as the throttle is gradually opened beyond a speed corresponding to fifty miles per hour level road car speed.

What I claim and desire to secure by Letters Patent of the United States is:

1. A carburetor of the character described, comprising a casing having a mixing chamber, an air inlet to said chamber, a mixture outlet from said chamber, a throttle controlling discharge from said outlet, a U-shaped conduit having one of the legs thereof operable to discharge fuel into said chamber, means to supply fuel to said one leg, the other leg of said conduit being open to the atmosphere, a normally open fuel jet, opening into said conduit, means to supply fuel to said jet, a valve controlling said jet, and means operable simultaneously with movement of said throttle to move said valve toward closed position to control the discharge of fuel into said chamber as said throttle is moved toward open position.

2. A carburetor of the character described, comprising a casing having a mixing chamber, an air inlet to said chamber, a mixture outlet from said chamber, a throttle controlling discharge from said outlet, a U-shaped conduit having one of the legs thereof operable to discharge fuel into said chamber, means to supply fuel to said one leg, the other leg of said conduit being open to the atmosphere, a normally open fuel jet opening into said conduit, means to supply fuel to said jet, a valve controlling said jet, and throttle-operated means operable to move said valve toward closed position to control the discharge of fuel into said chamber as said throttle is moved toward open position.

3. A carburetor of the character described, comprising a casing having a mixing chamber, an air inlet to said chamber, a mixture outlet from said chamber, a U-shaped conduit having one of the legs thereof operable to discharge fuel into said chamber, means to supply fuel to said one leg, the other leg of said conduit being open to the atmosphere, a normally open fuel jet opening into said conduit, means to supply fuel to said jet, and means to control discharge from said jet and simultaneously to accelerate the discharge of fuel from said conduit into said chamber.

4. A carburetor of the character described, comprising a casing having a mixing chamber, said chamber having an air inlet and main and supplemental fuel inlets, said chamber having an outlet, a throttle to control said outlet, means to supply fuel to said fuel inlets, and control means operable upon predetermined throttle opening movement to cut off the supply of fuel to said supplemental fuel inlet and operable upon predetermined further throttle opening movement to

reestablish fuel flow to said supplemental fuel inlet.

5. A carburetor of the character described, comprising a casing having a mixing chamber, said chamber having an air inlet and main and supplemental fuel inlets, said chamber having an outlet, a throttle to control said outlet, means to supply fuel to said fuel inlets, and throttle operated means operable to cut off the supply of fuel to said supplemental fuel inlet during a range of throttle movement between predetermined intermediate positions of throttle opening, whereby fuel is supplied to said mixing chamber only by said main inlet during said range of movement.

6. A carburetor of the character described, comprising a casing having a mixing chamber, said chamber having an air inlet and main and supplemental fuel inlets, said chamber having an outlet, a throttle to control said outlet, means to supply fuel to said fuel inlets, control means operable to cut off the supply of fuel to said supplemental fuel inlet during a range of throttle movement between predetermined intermediate positions of throttle opening, means to limit the air supplied by said air inlet, and means operable when the air supply is limited to prevent operation of said control means whereby fuel may be supplied from said supplemental inlet during the said range of throttle movement between predetermined intermediate positions of throttle opening.

7. A carburetor of the character described, comprising a casing having a mixing chamber, a mixture outlet from said chamber, a throttle to control said outlet, main fuel and air supply means opening into said chamber, supplemental fuel supply means to supply fuel to said chamber, throttle controlled means operable to cut off supply of fuel to said supplemental means upon a predetermined degree of initial throttle opening, and means operable substantially coincident with the operation of said throttle controlled means to accelerate the discharge of fuel from the supplemental supply means whereby the fuel mixture will have the increased proportion of fuel to air necessary for rapid acceleration.

8. A carburetor of the character described, comprising a casing having a mixing chamber, said chamber having a mixture outlet, a throttle to control said outlet, main fuel and air inlets to said chamber, supplemental fuel supply means to supply fuel to said chamber supplemental to the discharge from said main fuel inlet, means operable upon a predetermined degree of initial throttle opening to cut off supply of fuel to said supplemental means, means operable substantially coincident with said last-named means to accelerate discharge of fuel from said supplemental means, and means operable upon a predetermined degree of throttle opening to supply fuel to said supplemental means.

9. A carburetor of the character described, comprising a casing having a mixing chamber, an air inlet to said mixing chamber, a U-shaped conduit having a leg terminating in said inlet to discharge fuel to said mixing chamber, means to supply fuel to said leg, means to supply fuel to said conduit, a fuel chamber having communication with said conduit and being open to atmosphere, said fuel chamber having communication with said mixing chamber, and means to transfer fuel from said conduit to said fuel chamber for discharge into said mixing chamber.

10. A carburetor of the character described, comprising a casing having a mixing chamber, an

75

- air inlet to said mixing chamber, a U-shaped conduit having a leg terminating in said inlet to discharge fuel to said mixing chamber, means to supply fuel to said leg, a throttle to control discharge from said mixing chamber, means to supply fuel to said conduit, a fuel chamber having communication with said conduit and being open to atmosphere, said fuel chamber having communication with said mixing chamber, and a 5 throttle operated pump to transfer fuel from said conduit to said fuel chamber for discharge into said mixing chamber.
11. A carburetor of the character described, comprising a casing having a mixing chamber, an 10 air inlet to said chamber, a U-shaped conduit having a leg positioned in said air inlet to discharge fuel to said mixing chamber and having a plurality of atmospheric legs, means to supply fuel to said first-named leg, one of said atmospheric legs having a fuel chamber open to the atmosphere, means to supply fuel to said conduit, a nozzle discharging from said fuel chamber into said mixing chamber, and means in another of said atmospheric legs to transfer fuel from said 15 conduit to said fuel chamber for discharge into said mixing chamber.
12. A carburetor of the character described, comprising a casing having a mixing chamber, mixture control means, an air inlet to said chamber, a U-shaped conduit having a leg positioned in said air inlet to discharge fuel to said mixing chamber and having a plurality of atmospheric legs, means to supply fuel to said first-named leg, one of said atmospheric legs having a fuel 20 chamber open to atmosphere, means to supply fuel to said conduit, a nozzle discharging from said fuel chamber into said mixing chamber, and means actuated by said mixture control means and positioned in another of said atmospheric legs to transfer fuel from said conduit to said fuel chamber for discharge into said mixing chamber.
13. A carburetor of the character described, comprising a casing having a mixing chamber, a throttle to control discharge from said mixing chamber, an air inlet to said chamber, a U-shaped 25 conduit having a leg positioned in said air inlet to discharge fuel to said mixing chamber and having a plurality of atmospheric legs, one of said atmospheric legs having a fuel chamber open to atmosphere, means to supply fuel to said conduit, a fuel jet opening into said conduit, a nozzle discharging from said fuel chamber into said mixing chamber, and a throttle operated pump means in another of said atmospheric legs to transfer fuel from said conduit to said fuel chamber for discharge into said mixing chamber, said pump means controlling discharge from said fuel jet into said conduit.
14. A carburetor of the character described, comprising a casing having a mixing chamber, an air inlet passage to said chamber, a plurality of fuel inlets operable to discharge into said chamber, a fuel reservoir, means to supply fuel from said reservoir to one of said fuel inlets, a pump chamber having communication with the other of said fuel inlets, a fuel inlet port to said pump chamber from said reservoir, and a piston in said pump chamber operable to discharge fuel through said other fuel inlet, said piston having control means normally acting to permit fuel flow through said port into said pump chamber, said control means acting to cut off said port upon predetermined movement of said piston and to reestablish flow through said port upon further predetermined movement of said piston.
15. A carburetor of the character described, comprising a casing having a mixing chamber, a throttle to control discharge of mixture from said chamber, an air inlet passage to said chamber, a plurality of fuel inlets operable to discharge into said chamber, a fuel reservoir, means to supply fuel from said reservoir to one of said fuel inlets, a pump chamber having communication with the other of said fuel inlets, a fuel inlet port to said pump chamber from said reservoir, a piston in said pump chamber, spring means acting on said piston to cause said piston to discharge fuel through said other fuel inlet, said piston having control means normally acting to permit fuel flow through said port into said pump chamber, said control means acting to cut off said port upon predetermined movement of said piston and to reestablish flow through said port upon further predetermined movement of said piston, and means interconnecting said throttle and said piston, said means controlling the extent of piston movement by said spring means.
16. A carburetor of the character described, comprising a casing having a mixing chamber, an air inlet passage to said chamber, a U-shaped conduit having a fuel leg discharging in said chamber and having an atmospheric leg, means to supply fuel to said conduit, an idling tube depending into said atmospheric leg, a sleeve surrounding said tube in concentric spaced relation, said sleeve being circumferentially recessed at its upper end to provide an annular fuel chamber, a nozzle communicating with said fuel chamber and discharging into said mixing chamber, and means to transfer fuel from said conduit to said fuel chamber for discharge therefrom through said nozzle by gravity and atmospheric pressure.
17. In a carburetor, a mixing chamber, air and fuel supply means for said chamber, means to increase the ratio of fuel to air supplied to said chamber, means to accelerate discharge of fuel to said chamber, and means operable upon operation of said second-named means to render said accelerating means ineffective.
18. In a carburetor, a mixing chamber, air and fuel supply means for said chamber, a throttle controlling the discharge from said chamber, means to increase the ratio of fuel to air supplied to said chamber, throttle controlled means to accelerate discharge of fuel to said chamber, and means operable upon operation of said second-named means to render said accelerating means ineffective.
19. A carburetor of the character described, comprising a casing having a mixing chamber with an air inlet and a plurality of normally open fuel inlets, a throttle controlling discharge from said chamber, means to supply fuel to said fuel inlets, control means operable upon predetermined throttle opening movement to control discharge from one of said fuel inlets, means to increase the ratio of fuel relative to air supplied to said chamber, and means operable upon operation of said last-named means to render said control means ineffective.
20. A carburetor of the character described, comprising a casing having a mixing chamber with air and fuel inlets, a pump chamber communicating with said mixing chamber, a piston in said pump chamber operable to supply fuel to said mixing chamber, a normally open fuel inlet to said pump chamber, a valve rigid with said piston and operable on movement of said piston, to close said normally open fuel inlet, and

means operable upon continued movement of said piston to admit fuel to said pump chamber.

21. A carburetor of the character described, comprising a casing having a mixing chamber with air and fuel inlets, a pump chamber communicating with said mixing chamber, a piston in said pump chamber operable to supply fuel to said mixing chamber, a normally open fuel inlet to said pump chamber, a valve controlling said normally open fuel inlet, said piston being operable to move said valve to close said normally open inlet, and being operable upon further movement to permit flow through said normally open inlet.

22. A carburetor of the character described, comprising a casing having a mixture passageway therethrough with air and fuel inlets and a mixture outlet, a fuel reservoir, a conduit leading from said reservoir to said passageway, a normally open valve controlling said conduit and movable to full closed position, means normally acting to close said conduit valve, a valve controlling said air inlet, and normally ineffective means movable into engagement with said normally acting means on movement of said air inlet valve toward closed position thereby to render said normally acting means ineffective to close said conduit valve.

23. A carburetor of the character described, comprising a casing having a mixture passageway therethrough with air and fuel inlets and a mixture outlet, a fuel reservoir, a conduit leading from said reservoir to said passageway, a normally open valve controlling said conduit and movable to full closed position, a throttle valve controlling said outlet, means operable on opening movement of said throttle valve to move said conduit valve toward closed position, a valve controlling said air inlet, and means operable on movement of said air inlet valve toward closed position to render said last-named means ineffective to close said conduit valve.

24. A carburetor of the character described, comprising a casing having a mixture passageway therethrough with air and fuel inlets and a mixture outlet, a fuel reservoir, a conduit leading from said reservoir to said passageway, a valve controlling said conduit and movable to full closed position, a spring normally tending to move said conduit valve toward closed position, means operable to release said spring for valve closing movement, a valve controlling said air inlet, and means operable on movement of said air inlet valve toward closed position to render said first-named means ineffective to release said spring.

25. A carburetor of the character described, comprising a casing having a mixture passageway therethrough with air and fuel inlets and a mixture outlet, a throttle valve controlling said outlet, a fuel reservoir, a conduit leading from said reservoir to said passageway, a valve movable to full closed position and controlling said conduit, a spring operable to move said conduit valve to closed position, throttle-operated means operable to release said spring for valve closing movement, a valve controlling said air inlet, and means actuated by movement of said air inlet valve toward closed position to render said throttle operated means ineffective to release said spring.

26. A carburetor of the character described, comprising a casing having a mixture passageway therethrough with air and fuel inlets and a mixture outlet, a fuel reservoir, a conduit leading from said reservoir to said passageway, a

normally open valve controlling said conduit and movable to full closed position, means normally acting to move said conduit valve to closed position, a valve controlling said air inlet, a cam operable by said air inlet valve, and means actuated by said cam and operable to render said last-named means ineffective to close said conduit valve.

27. A carburetor of the character described, comprising a casing having a mixture passageway therethrough with air and fuel inlets and a mixture outlet, a fuel reservoir, a conduit leading from said reservoir to said passageway, a normally open valve movable to full closed position and controlling said conduit, a valve having a shaft and controlling said air inlet, means normally acting to close said conduit valve, a lever movable into engagement with said normally acting means to hold said conduit valve in open position, a cam carried by said shaft and engageable with said lever, and means urging said lever into engagement with said cam and into holding relation to said valve closing means whereby to move said lever into holding position on movement of said air valve toward closing position.

28. A carburetor of the character described, comprising a casing having a mixing chamber, an air inlet passage to said chamber, a plurality of fuel inlets operable to discharge into said chamber, a fuel reservoir, means to supply fuel from said reservoir to one of said fuel inlets, a fuel chamber having communication with the other of said fuel inlets, a fuel inlet port from said reservoir to said fuel chamber, a throttle valve controlling discharge from said mixing chamber, a reciprocable valve movable into and through said port, and means interconnecting said valves, said reciprocable valve being normally open and being operable upon predetermined throttle opening movement to close said port, said reciprocable valve having means operable upon further throttle opening movement to reestablish flow through said port.

29. A carburetor of the character described, comprising a casing having a mixing chamber, an air inlet passage to said chamber, a plurality of fuel inlets operable to discharge into said chamber, a fuel reservoir, means to supply fuel from said reservoir to one of said fuel inlets, a fuel chamber having communication with the other of said fuel inlets, a fuel inlet port from said reservoir to said fuel chamber, a throttle valve controlling discharge from said mixing chamber, a valve member having a substantially conical valve face controlling flow through said port, said valve member having a stem and being movable into and through said port, said stem having a longitudinal passageway with an inlet adjacent said valve face and an outlet spaced longitudinally therefrom, and means interconnecting said stem and said throttle valve whereby on throttle opening movement said valve member will close said port and upon further throttle opening movement said stem inlet will be moved through said port to permit flow through said stem into said fuel chamber.

30. A carburetor of the character described, comprising a casing having a mixing chamber, an air inlet passage to said chamber, a plurality of fuel inlets operable to discharge into said chamber, a fuel reservoir, means to supply fuel from said reservoir to one of said fuel inlets, a pump chamber having communication with the other of said fuel inlets, a fuel inlet port to said pump chamber from said reservoir, a piston in

75

said pump chamber operable to discharge fuel through said other fuel inlet, a valve member rigid with and projecting from said piston, said valve member being movable by said piston into 5 said port to cut off flow therethrough, and a by-pass passage through said valve member operable upon continued movement of said piston to reestablish flow through said port.

31. In a carburetor, a mixing chamber, main air and fuel inlets to said chamber, a valve controlling said air inlet, means to accelerate discharge of fuel into said chamber, and means operable upon closing movement of said air inlet valve to render said accelerating means ineffective. 5

WALTER H. WEBER.
